UNITED STATES PATENT OFFICE.

HARRY E. DOERR, OF ST. LOUIS, MISSOURI, ASSIGNEE TO SCULLIN STEEL CO., OF ST. LOUIS, MISSOURI, A CORPORATION OF MISSOURI.

SIDE FRAME FOR TRUCKS.

Application filed March 27, 1924. Serial No. 702,191.

To all whom it may concern:

Be it known that I, HARRY E. DOERR, a citizen of the United States, residing at St. Louis, in the State of Missouri, have invented certain new and useful Improvements in Side Frames for Trucks, of which the following is a specification.

This invention relates to a new and improved side frame for trucks and more particularly to a pressed steel side frame having a journal box formed integrally therewith.

Various types of pressed steel side frames have heretofore been made, but such frames have had separately formed journal boxes secured thereto. These boxes have usually been held in place by bolts, which connection is unsatisfactory for taking care of load stresses as it tends to work loose under service vibrations.

It is an object of the present invention to provide a pressed steel side frame construction in which a journal box is formed integrally therewith.

It is a further object to provide construction of this character in which the side frame is formed of two portions joined on a median plane with a journal box formed of two portions similarly joined.

It is an additional object to provide a construction of this character in which the side frame and journal box portions are so formed that each portion has complete wall structure.

It is also an object to provide a construction in which the adjacent portions of the journal box and side frame are formed by reverse bends, the folds of the reverse bends of the two side frame portions being welded together.

Other and further objects will appear as the description proceeds.

I have illustrated a preferred embodiment of my invention in the accompanying drawing, in which—

Figure 1 is a plan view of one-half of a side frame and journal box;

Figure 2 is a face view of Figure 1;

Figure 3 is an end view of Figure 1 as seen from the left;

Figure 4 is a section taken on line 4—4 of Figure 2; and

Figure 5 is a section taken on line 5—5 of Figure 2.

The side frame consists in two side frame

members 11 and 12 which are welded together on the median line 13. As shown in section 4—4, certain portions of the frame are completely closed, the two frame members being U shaped in cross section and both legs of the U meeting. Other portions such as the tension member 14, shown in cross section in Figure 5, are open on one side, one leg of the U being longer than the other.

The journal box comprises two portions 15 and 16. The portion 15 is integral with the side frame portion 12 and the portion 16 is integral with the side frame portion 11. The journal box portion 15 has a hinge member 17 welded thereto, and the member 18 is welded into the journal box portion 16 to form a pocket for the usual type of dust guard. As shown in Figure 1, the side of the journal box adjacent the side frame is formed by portion 19 which is connected by the reverse bend 20 with the side 21 of the side frame. The side of portion 16 of the journal box is similarly connected by a reverse bend to the side frame member 11.

As shown in Figure 3 the upper surface 22 of the journal box portion 15 is connected by the reverse bend 23 with the lower face 24 of the end of the side frame member 12. The upper surface of the journal box portion 16, as shown in Figure 3, is similarly connected to the side frame member 11. These two reverse bends meet on the median plane and are welded together as indicated at 25.

The construction shown permits the formation of the journal box at the same time that the two side frame members are formed. The two portions of the journal box are welded together as the side frame members are welded. The dust guard retaining member 18 will be welded in place in the portion 16 of the journal box before the two faces are joined and the plates 26 and 27 may be similarly put in place before the joining 100 welds are made.

This construction affords a journal box rigidly and permanently connected to the side frame. While I have shown one specific embodiment of such a construction by way of example, I contemplate changes and modifications to meet varying conditions and requirements, such as come within the spirit and scope of the following claims.

I claim:

105

110

1. Truck side frame construction comprising a pressed steel side frame and a pressed steel journal box formed integrally with the side frame.
2. Truck side frame construction comprising a pressed steel side frame, the side frame being formed of two pressed steel members joined by welding on a vertical longitudinal plane and a journal box, portions of the box being formed integrally with each of the two pressed steel side frame members.
3. Truck side frame construction comprising a pressed steel side frame, the side frame being formed of two pressed steel members joined by welding on a vertical longitudinal plane and a journal box, portions of the box being formed integrally with each of the two pressed steel side frame members, said portions being welded together in the same plane as the side frame members.
4. Truck side frame construction comprising a pressed steel side frame, the side frame being formed of two pressed steel members

joined by welding on a vertical longitudinal plane and a journal box, portions of the box being formed integrally with each of the two pressed steel side frame members said portions being connected to the side frame portions by reverse folds whereby side frame and box walls are located adjacent to each other.

5. Truck side frame construction comprising a pressed steel side frame, the side frame being formed of two pressed steel members joined by welding on a vertical longitudinal plane and a journal box, portions of the box being formed integrally with each of the two pressed steel side frame members, said portions being connected to the side frame portions by reverse folds whereby side frame and box walls are located adjacent to each other, the reverse folds of the two side frame members abutting and being welded together.

Signed at St. Louis, Mo., this 24th day of March, 1924.

HARRY E. DOERR.
